UNITED STATES PATENT OFFICE.

KARL BODE, OF NEW YORK, N. Y., ASSIGNOR OF ONE-HALF TO THOMAS J. BUCHANAN, OF YONKERS, NEW YORK.

BOTTLE-HOLDER.

No. 884,355.

Specification of Letters Patent.

Patented April 14, 1908.

Application filed January 30, 1908. Serial No. 413,379.

To all whom it may concern:

Be it known that I, KARL BODE, a citizen of Germany, residing at New York city, Manhattan, county and State of New York, have 5 invented new and useful Improvements in Bottle-Holders, of which the following is a specification.

This invention relates to a box or other receptacle adapted to be attached in such a place, preferably in front of a dwelling, as to 10 be readily accessible to a milkman or other deliverer of wet goods.

The construction of the holder is such that the milkman can readily open an empty box, 15 or a box containing a reversed empty bottle, without a key, whereas, the holder containing a filled bottle, can only be opened by means of a key. Thus, any unauthorized abstraction of the filled bottles is prevented, 20 while the milkman is not burdened with carrying a large number of keys, nor is he taxed with their manipulation while delivering his goods.

In the accompanying drawings: Figure 1 25 is a front view of my improved bottle holder; Fig. 2 is a vertical section thereof; Fig. 3 a horizontal section on line 3—3, Fig. 2; Fig. 4 a vertical section of the holder, showing it charged with an empty bottle; Fig. 5 a cross section on line 5—5, Fig. 2, and Fig. 6 a section through the hinge of the pivoted front on line 6—6, Fig. 2.

A box or other receptacle 10, adapted to accommodate one or more bottles of milk or 35 other wet goods, is provided with a hinged front 11, which is fulcrumed to the sides of the box at or near its center, as at 12. When the front is in its upright position, it strikes with its upper section an inner abutment 13, 40 while it strikes with its lower section an outer abutment 14, but if desired, one of such abutments may be dispensed with. At its top, front 11 carries a lock 15 adapted to engage a catch 16 depending from the hinged cover 45 17 of the box. The construction is such that even when the lock is closed, the front may be turned upon its pivot, provided it is not obstructed by the contents of the box. To effect this result, the back-plate 18 of the 50 lock is recessed opposite the operative ends of

the locking bolts 19, that are adapted to engage catch 16 by a sidewise movement.

Near its bottom, hinged front 11 is provided with an inwardly extending beveled projection 21 adapted to engage the bottle 22 55 placed into the holder. One or more springs 23 tend to righten and thereby close the front as soon as the same is unlocked.

The operation is as follows: The receptacle being locked empty, the milkman 60 pushes against lower end of hinged front 11, to disengage lock 15 from catch 16 and thereby open the lock without the use of a key. The milkman now raises lid 17, places a filled bottle of milk into the box and closes the lid 65 upon the front 11, which has been righted by springs 23, so that catch 16 snaps into engagement with spring bolts 19 and the box becomes re-locked. If an unauthorized person tries to open the box by pressing against 70 the lower end of front 11, his efforts will be unavailing, because the shoulder 21 striking the body of the bottle, will prevent the front 11 from swinging inwards at its bottom, (Fig. 2). The house-keeper having the 75 proper key may, however, unlock the box, remove the filled bottle and then re-lock the box. If the house-keeper desires to return an empty bottle, he places it in a reversed position into the box. As in this case 80 the contracted neck 20 of the bottle is spaced from shoulder 21, the box front 11 may be readily swung inwards at its bottom, (Fig. 4), to open the box without the use of a key.

It will be seen that by my invention the 85 milkman may readily open the various boxes without the use of keys, while, as soon as a box is filled, it can no longer be so opened. In this way the manipulation is simplified and a safe delivery insured, while, furthermore, empties may be readily returned.

I claim:

1. A bottle holder comprising a receptacle having a hinged top, a front pivoted between its upper and lower ends, and means for locking the top to the front without preventing a tilting of the front, substantially as specified.

2. A bottle holder comprising a receptacle having a hinged top, a front pivoted between 100

2
its upper and lower ends, a recessed lock on one of said parts, and a catch on the other part adapted to engage said lock, substantially as specified.

3. A bottle holder comprising a receptacle having a hinged top, a front pivoted between its upper and lower ends, a shoulder on the front, and means for locking the top to the

front without preventing a tilting of the front, substantially as specified.

Signed by me at New York city, (Manhattan,) N. Y., this 29 day of January, 1908.

KARL BODE.
